SPRAYING APPARATUS

Henry James Newlin, Birmingham, England

Application May 1, 1935, Serial No. 19,280

2 Claims. (Cl. 299—140.1)

This invention relates to spraying apparatus for liquids or other material, of the type in which air and a liquid or material to be sprayed are fed to a discharge nozzle, and the present invention particularly relates to spraying apparatus set forth in the specification accompanying my application for Patent Serial No. 8351 of 1935.

The invention has for its object a simplified construction whereby the control trigger or device actuates both the liquid or like control valve and valve mechanism controlling the air feed for obtaining, at will, either a round spray or a fan-shaped spray. A further object of this invention is to obtain a valve mechanism for controlling the air feed which is not liable to get out of order and which is readily adjustable. A further object of this invention is to enable the air feed for obtaining the fan-shaped spray to be adjustable to obtain the desired form of fan-shaped spray.

20 Referring to the drawing:—

Figure 1 is a cross sectional elevation of a spray gun constructed according to this invention, and

Figure 2 is a section on line 2—2 of Figure 1.

According to a convenient embodiment of this invention, the gun comprises a frame 1 in which is mounted the liquid spray needle valve 2 coacting in the usual manner with the spray nozzle, the liquid being fed through a suitable duct 3. The liquid control valve 2 is actuated by a trigger 4 pivoted on the frame and having a pin 5 which moves against an adjustable collar 6 on the valve spindle.

The lower portion of the frame, below said needle valve, has a stepped bore 7 into which is fitted a fixed valve seat 8. The compressed air enters the air chamber 9, by way of the duct 9a, and passes through the opening in the valve seat 8 into the second air chamber 10. An air control valve 11 is normally pressed by the spring 12 to close the valve opening and such valve 11 is carried by a valve sleeve 13 slidably mounted in the gland 14. The valve 11 has a seating washer 11a fitted in a recess in its face. A nut 15 is screwed on the said sleeve 13 and forms an adjustable abutment member or stop. A link 16 is pivoted at one end to the trigger 4 whilst the other end is engaged on the valve sleeve 13 between the said abutment nut 15 and a lock nut 15a. An air conduit 17 passes from the said second air chamber 10 and feeds compressed air to the air cap 18 to give the round spray. A conduit 19 passes from the end of the said second air chamber 10 to the air cap 18 to give the fan-shaped spray. The conduit 19 is closed to the air feed by means of a second valve 20 which seats on a fixed seating 21,

the valve 20 being fixed on a valve spindle 22 which is slidably mounted in the valve sleeve 13 aforementioned. The end of this spindle 22 projects beyond the abutment nut 15 fixed on the valve sleeve 13 and the end of the valve spindle is 5 fitted with a screwed adjustable abutment nut 23.

The conduit 19 passes to and from the conical valve seat 24 and the passage of air through the conduit 19 is regulated by a conical valve 25 which is screw-threaded for engaging a tapped hole in 10 the frame 1. The valve spindle 25 passes through a packing gland and terminates in a knurled head 26 for adjusting the valve and consequently the flow of air to the air cap for producing the fan-shaped spray.

With the aforescribed construction, when the trigger 4 is first moved, the link 16 bears against the abutment nut on the valve sleeve 13 and moves the valve 11 from its seating. Air then flows through the first air chamber 9 into the 20 second air chamber 10 and through the conduit 17 to the air cap. On the further movement of the trigger 4, the liquid control needle valve 2 is opened to supply liquid to the nozzle. Under these conditions a round shaped spray is obtained. 25 If it is required to produce a fan-shaped spray, the trigger 4 is pulled further back, until the screwed abutment nut 15 on the valve sleeve 13 bears against the nut or stop 23 on the spindle of the second valve, to thereby pull back the second 30 valve 20 against the pressure of the spring 27. In this latter position of the trigger, air will pass through both conduits 17 and 19 leading to the air cap. By adjusting the valve 25, in the conduit 19 feeding air for producing the fan-shaped spray, 35 the desired form of spray can be obtained.

I claim:

1. Apparatus for spraying liquids or other materials, comprising a frame, a control valve for the liquid or material to be sprayed, slidably mounted in the frame under control of a spring, a spraying nozzle at which occurs, alternatively, round and fan shaped sprays on said frame, a trigger lever for actuating said liquid control valve pivotally mounted at its upper end on said frame, an abutment on said valve against which the said trigger lever is pressed to open the valve and which abutment is spaced from the trigger when in the inoperative position, a chamber in the frame for receiving compressed air 40 from the source of supply, a second air chamber in the frame in alignment with the aforementioned chamber, an air control valve coacting with a fixed seating at the junction of and controlling communication between said chambers, 45 50 55

a sleeve on the said air valve and slidably mounted under spring control in the frame under the said liquid control valve, a spring normally pressing the valve on its seating, an air conduit leading from said second chamber for supplying air to produce a round spray, a second air valve spring pressed on a fixed seating and controlling communication between the second air chamber and an air conduit for supplying air to produce a fan-shaped spray, a spindle on this second air valve slidably mounted in and projecting beyond the said valve sleeve, means whereby the said first air valve, the liquid valve and the second air valve are successively opened by pressure applied by the said trigger in one direction to obtain either a round or a fan-shaped spray and whereby the spring controlling the first mentioned air valve controls the position of the trigger lever in the inoperative position, and a separate valve mounted on the frame for controlling the flow of air through the said conduit supplying air to produce the fan-shaped spray in order to ensure a predetermined balance of air passing through the two conduits leading to the spraying nozzle to form a fan-shaped spray.

2. Apparatus for spraying liquids or other materials, comprising a frame, a control valve for the liquid or material to be sprayed, a spraying nozzle at which occurs, alternatively, round and fan-shaped sprays on said frame, a trigger lever for actuating said liquid control valve pivotally mounted at its upper end on said frame, an abutment on said valve against which the said trigger lever is pressed to open the valve and which abutment is spaced from the trigger when in the inoperative position, a chamber in the frame for

receiving compressed air, a conduit pipe for delivering compressed air from a source of supply to said chamber and passing through a hand grip fixed to the frame, a second air chamber in the frame in alignment with said chamber, an air control valve coacting with a fixed seating at the junction of and controlling communication between said air chambers, a sleeve on the said air valve and slidably mounted under spring control in the frame under the said liquid control valve, a spring normally pressing the said valve on the seating, an air conduit leading from said second air chamber for supplying air to produce a round spray, a second air valve spring pressed on a fixed seating and controlling communication with an air conduit for supplying air to produce a fan-shaped spray, a spindle on this second air valve slidably mounted in and projecting beyond the said valve sleeve, a lever connected at one end to the trigger lever and at its other end engaged on the outer end of the said valve sleeve, so that the valve sleeve is moved on the initial movement of the trigger lever to admit air to the spraying nozzle and so that the said spring controlling the movement of the valve sleeve returns the trigger to its inoperative position, an adjustable stop on the end of the valve sleeve projecting from the rear end of said frame against which stop the lever presses for opening the first mentioned air valve, and a stop on the projecting end of the spindle of the said second air valve, which stop is pressed against on the movement of the valve sleeve for opening the said second air valve.

HENRY JAMES NEWLIN.
